UNITED STATES PATENT OFFICE

165,751

VENDING MACHINE OR SIMILAR ARTICLE

Fred Hebel, Chicago, Ill., assignor to Fred Hebel Corporation, Chicago, Ill., a corporation of Illinois

Application July 13, 1950, Serial No. 11,109

Term of patent 14 years

(Cl. D52—3)

To all whom it may concern:

Be it known that I, Fred Hebel, a citizen of the United States and a resident of the city of Chicago, in the county of Cook, and State of Illinois, have invented a new, original, and ornamental Design for a Vending Machine or Similar Article, of which the following is a specification, reference being had to the accompanying drawing forming a part thereof.

On the drawing:

Figure 1 is a front view, slightly in perspective, of a vending machine, or similar article, showing my new design; and

The side of the vending machine not disclosed is essentially the same in appearance as the side shown.

I claim:

The ornamental design for a vending machine or similar article, as shown and described.

FRED HEBEL.
